UNITED STATES PATENT OFFICE

2,361,727

RADIAL ENGINE

Paul W. Winter, Arkansas City, Kans.

Application April 15, 1943, Serial No. 483,183

1 Claim. (Cl. 123—171)

The present invention relates to new and useful improvements in radial engines, and has for its primary object to provide, in a manner as hereinafter set forth, a power plant of this type comprising an air cooling system embodying a novel construction and arrangement whereby all of the cylinders will be uniformly and efficiently cooled.

Other objects of the invention are to provide a radial, air cooled engine of the character described which will be comparatively simple in construction, strong, durable, highly efficient and reliable in operation, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of an engine constructed in accordance with the present invention, the upper portion of the cooling system being broken away in vertical longitudinal section.

Figure 2 is a view in front elevation of the engine with a portion of the cooling means broken away in section.

Figure 3 is a view in vertical section through one of the cylinders.

Figure 4 is a vertical sectional view through one of the cylinders taken at right angles to Figure 3.

Figure 5 is a view in horizontal section, taken substantially on the line 5—5 of Figure 3, showing one of the cylinders in top plan.

Figure 6 is a top plan view of one of the cylinder jackets.

Figure 7 is a fragmentary view in elevation, looking at the upper rear portion of the engine substantially from the line 7—7 of Figure 1.

Referring now to the drawings in detail, it will be seen that reference numeral 1 designates an elongated crank case having journaled longitudinally therein a crank shaft 2. Banks of cylinders 3 radiate from the crank case 1. The cylinders 3 are provided with renewable liners 4. Pistons 5 are operable in the cylinders 3, said pistons being connected in the usual manner to the crank shaft 2 by rods 6.

Mounted longitudinally on the walls and the heads of the cylinders 3 are heat dissipating fins 7. If desired, the fins 7, the heads 8, the cylinders 3, et cetera, may be integral.

Air jackets 9 enclose the fins 7 in spaced, con-

centric relation to the cylinders 3, said jackets projecting beyond the heads 8 of the cylinders. The outer ends of the jackets 9 are partially closed by covers 10 which are formed to provide 5 openings 10a at the outer ends of jackets 9 (Fig. 6). Intake and exhaust passages 11, for connection with suitable manifolds (not shown) communicate with the cylinders 3 through the heads 9 thereof. Valves 12 control the passages 11, said 10 valves being opened by rocker arms 13, push rods 14, et cetera. The stems 15 of the valves 12 are 15 slideable in vertical guides 16 which are provided therefor in the walls of the passages 11. In addition to the elements 13, 14, et cetera, the fins 7 are also arranged to accommodate spark plugs 17 in the cylinder heads 8. It will be observed that the inner ends of the air jackets 9 are spaced from the crank case 1.

Annular baffles 18 encircle the crank case 1 in 20 back of each ring or circle of the cylinders 3. As illustrated to advantage in Figure 1 of the drawings, the outer diameter of the annular baffles 18 progressively increases from the first to the last of said baffles. The baffles 18, with the exception 25 of the rearmost thereof, are provided, on their outer peripheries, with forwardly projecting flanges 19. The flanges 19 are cut out or recessed at spaced points to accommodate the air jackets 9.

30 In lieu of a flange 19, the rearmost baffle 18 has formed integrally therewith a forwardly projecting tubular or annular cowl 20 or attached to rear inner wall 21 which encircles the crank case 1 in spaced concentric relation thereto. The 35 annular cowl 20 comprises spaced inner and outer walls 21 and 22, respectively, forming a chamber 23 which is open at its rear end. The outer wall 22 diverges rearwardly from the inner wall 21 of the cowl 20. Thus, the chamber 23 progressively increases in size or capacity toward 40 its rear end to equal the space between the cowl 20 and the crank case 1 at the front of the engine. The outer portions of the air jackets 9 project into the cowl 20 through the inner wall 21 thereof and communicate with the chamber 23.

45 It is thought that the manner in which the invention functions will be readily apparent from a consideration of the foregoing. Briefly, air 50 from the atmosphere enters the annular cowl 20 around the crank case 1, being forced in by the revolving propeller attached to the front of the crank shaft 2, the air jackets 9, et cetera. This air is trapped in equal amounts by the successive baffles 18 and enters the jackets 9 at the

inner ends thereof. As the engine travels forwardly, suction is created in the chamber 23 with the result that the air is drawn rapidly through the jackets 9 between the fins 7 and around the cylinders 3 into the chamber 23. The construction and arrangement is such that the jackets 9 receive substantially equal quantities or volumes of air for uniformly cooling all of the cylinders 3. If desired, the cylinders 3 may be provided with relatively shallow cooling fins from the inner ends of the jackets 9 to the crank case 1.

It is believed that the many advantages of a radial engine comprising a cooling system in accordance with the present invention will be readily understood, and although a preferred embodiment is as illustrated and described, it is to be understood that changes in the details of construction and in the combination and arrangement of parts may be resorted to which will fall within the scope of the invention as claimed.

What is claimed is:

In a radial internal combustion engine, an elongated tubular crankcase, a plurality of banks of cylinders radiating from said crankcase, ex-

ternal longitudinal fins on the outer portions of said cylinders having lateral extensions at their outer ends extending across the heads of said cylinders, air jackets enclosing said fins and having outer end walls provided with air outlet openings, the inner ends of said jackets being spaced from the crankcase for admission of air therein, radial annular baffles on the crankcase projecting outwardly between adjacent banks of the cylinders for progressively increasing distances from front to rear of the motor, forwardly projecting annular flanges on the outer edges of all but the rearmost one of said baffles and recessed to receive and partially embrace the cylinders, and a hollow tubular cowl encircling the crankcase in spaced concentric relation to the latter and including rearwardly diverging annular inner and outer walls defining a chamber therein closed at the front and open at the rear, the other portions of said jackets projecting through the inner wall of said cowl into said chamber thereof, the rear edge of the inner wall of the cowl connecting with the outer edge of the rearmost baffle.

PAUL W. WINTER.
